UNITED STATES PATENT OFFICE.

CHARLES J. KOENIG, OF NEW BALTIMORE, MICHIGAN.

COLLECTION-RECEPTACLE.

1,400,823.

Specification of Letters Patent. Patented Dec. 20, 1921.

Application filed February 21, 1921. Serial No. 446,851.

To all whom it may concern:

Be it known that I, CHARLES J. KOENIG, a citizen of the United States of America, residing at New Baltimore, in the county of 5 Macomb and State of Michigan, have invented new and useful Improvements in Collection-Receptacles, of which the following is a specification, reference being had therein to the accompanying drawings.

10 This invention relates to collection or contribution boxes, pertaining more particularly to boxes or receptacles used in receiving contributions in churches, etc.

Collections are generally taken up by the 15 passage of a suitable receptacle, such as a basket, plate, box, etc., in which the successive contributions remain exposed, excepting as they may be covered by other contributions. This has the disadvantage that 20 in heavy collections the entire amount previously contributed is exposed to view to the various individuals as they are reached, and makes possible accidental spilling of the contents as the receptacle is passed from 25 hand to hand. Another disadvantage, present with large or small collections, is in the inability of the contributor to find a support for the contribution pledge when called upon to write the pledge at the time the 30 contribution is made; in some congregations pledges of this kind are given frequently, and where the collection receptacle is of the type indicated, the presence of previous contributions in the receptacle prevents the use of the receptacle as such a 35 support.

Attempts have been made to overcome some of these disadvantages by the use of a receptacle carrying a false bottom—tiltable—arranged near the top of the receptacle, tilting of the bottom permitting the collections to be deposited in a lower receiving portion. In such structures, the false bottom is in the form of a flat plate corresponding in contour to the contour of the opening in which it is located, and in tilting, the plate must be turned to at least 90° from the horizontal—generally to a greater extent—to insure proper deposit of the collections on the plate or tray. This not only involves delay in manipulation, but also requires actual manipulation to provide for returning the tray to proper position. And this difficulty also brings in the difficulty 55 of producing an efficient support for writ-

ing of pledges, since the tray axis must be on a diameter of the tray and any attempt at use as a support in writing is made difficult through instability of the tray.

The present invention is designed to produce a receptacle for this purpose in which these and other difficulties are overcome by a simple arrangement, which is efficient in operation, durable in construction, and which can be manufactured at a relatively 60 low cost.

To these and other ends, the nature of which will be readily understood as the invention is hereinafter disclosed, said invention consists in the improved construction 70 and combination of parts hereinafter more fully described, illustrated in the accompanying drawings, and more particularly pointed out in the appended claims.

In the accompanying drawings, in which 75 similar reference characters indicate similar parts in each of the views—

Figure 1 is a top plan view of a preferred embodiment of the invention.

Fig. 2 is a sectional view of the same, 80 taken on line 2—2 of Fig. 1.

Fig. 3 is a sectional view taken on line 3—3 of Fig. 1.

In the drawing I have shown one embodiment of the present invention; obviously, it 85 may have other forms, that shown being a preferred form. In this form the body of the receptacle is in the form of a metallic open-top container 10, of suitable contour—shown as circular—and of desired depth, a 90 handle 11 being employed for carrying it about. The bottom of the container is preferably covered by a suitable fabric layer 12, which may be of felt or other suitable material, its use permitting coins to drop 95 thereon without setting up the metallic sounds produced when coins are dropped on to a metallic bottom.

13 indicates the receiving tray or false bottom, this being shown as having a flat bottom 100 portion 13^a and an upstanding flange 13^b, these forming a tray of suitable depth—relatively shallow as compared with the depth of the container. The tray is shown as connected to a rod 14 extending across the 105 container below bottom 13^a to which it is connected, the rod carrying a handle portion 14^a. The rod is preferably located on a diameter of the container, but it may vary from this position within certain limits. A stop 110

or seat 15 is carried by the container and on which the tray rests when in its contribution-receiving position; the stop is preferably arranged in position at a right angle 5 to the diameter on which rod 14 extends, although this position may also vary and more than a single stop may be employed at spaced points, if desired.

The tray is preferably cut-away or recessed, as at 13°, on the side opposite the stop 15 this recessed portion including both bottom 13^a and flange 13^b, the recess being of suitable length radially of the tray, and extending inward from the line which would 15 complete the circle of the tray. Of course, where the contour of the container or tray is other than circular, the recess would conform to the changed form.

The bottom of the tray is preferably covered with the fabric layer 16, and if desired the inner face of flange 13^b may also carry such a layer.

Since the tray is of flanged form, its diameter is less than that of the interior of the 25 container, sufficient space being left between the two as to permit the proper tilting action to take place.

The advantages of this arrangement will be readily understood. The tray may be 30 mounted on a diameter of the container and yet carry the characteristics of a weighted tray, since the removal of the material to provide the recess 13° serves to produce an unbalanced condition to the tray, with the 35 heavier portion on that side of the pivot below which is located stop or stops 15. As a result, the tray will normally remain in its receiving position, especially since the deposit of coins would tend to set up a preponderance of weight on the unrecessed side, the presence of the recess permitting coins 40 to drop through if the collection would place them in position relative to the recess. In dumping the collection, the coins begin to 45 pass into the container with a slight tilting action, the flange directing them toward the recess, so that the tray need not be tilted beyond the 90° point; where the contribution is a bill, it can be readily passed through 50 the recess, as can pledges. In addition, the structure provides an efficient writing support for one making a written pledge, since the tray is normally maintained in position, and the visual presence of the recess permits 55 the writer to be guided in positioning the paper to be written upon, the unrecessed portion of the bottom offering a better writing support than that portion carrying the recess because of greater area; so that the 60 recess not only acts as an indicator of position but as a deterrent to positioning the paper on the side which is unsupported.

Since the tray is flanged, the contributions 65 collected between successive tiltings of the tray are all retained within the tray itself,

there being no possibility of being brought into contact with the wall of the container; hence there is no liability of contributions being carried out of the receptacle by the tilting operation, such as might occur where 70 the coin rests against the container wall of a receptacle using a flat false bottom.

While I have herein shown and described a preferred embodiment of the invention, it 75 will be readily understood that changes and modifications therein may be found desirable or essential in meeting the exigencies of use or the taste of the user, and I desire to be understood as reserving the right to make any and all such changes or modifications as 80 may be found essential or desirable in so far as the same may fall within the spirit and scope of the invention as expressed in the accompanying claims.

Having thus described my invention, what 85 I claim as new is:

1. In a collection receptacle, a container having an open top, a handle projecting laterally therefrom, and a tray tiltably supported in the open end of the container, said tray being recessed inwardly on the unsupported side of its pivot, said recess providing communication with the interior of the container in the plane of the collection-receiving face of the tray, the dimension of 95 the recess inward from the tray periphery being less than the diameter of a coin.

2. In a collection receptacle a container having an open top, a handle projecting laterally from the container, and a tray tiltably mounted in such open end with the pivot point extending substantially diametrical of such end, a support carried by the container on one side of the tray pivot, said tray being recessed inwardly on the opposite 105 side of the pivot, said recess providing communication with the interior of the container in the plane of the collection-receiving face of the tray, the dimension of the recess inward from the tray periphery being 110 less than the diameter of a coin.

3. A collection receptacle as in claim 1 characterized in that the tray is formed with a peripheral upstanding flange, with the flange length and position such as to maintain the recess and prevent interruption of the communication when the tray is tilted. 115

4. In a collection receptacle, a container having an open top, a handle projecting laterally from the container, and a tray tiltably supported in the open top of the container, said tray having a bottom and an upstanding peripheral flange, said flange and bottom being recessed inwardly from the peripheral line of the tray with the recess dimensions such as to provide communication with the interior of the container in the plane of the bottom of the tray and within the line of the flange, and a support 125 for the tray, said support and said recess 130

being positioned on opposite sides of the pivot line of the tray.

5. A collection receptacle as in claim 1 characterized in that the bottom of the container and the collection-receiving face of the tray are provided with a fabric layer.

6. A collection receptacle as in claim 4 characterized in that the bottom of the container, and the tray bottom and internal face

of the tray flange are provided with a fabric 10 layer.

In testimony whereof I affix my signature in presence of two witnesses.

CHARLES J. KOENIG.
